(57) **CLAIM**

The ornamental design for a dual reciprocating saw, as shown and described.

DESCRIPTION

FIG. 1 is a front elevation view of a dual reciprocating saw showing my new design;

FIG. 2 is an opposite side front elevation view of a dual reciprocating saw of FIG. 1;

FIG. 3 is a front end view of the dual reciprocating saw of FIG. 1;

FIG. 4 is a side plan view of the dual reciprocating saw of FIG. 1;

FIG. 5 is an opposite side plan view of the dual reciprocating saw of FIG. 1;

FIG. 6 is a top view of the dual reciprocating saw of FIG. 1;

FIG. 7 is a bottom view of the dual reciprocating saw of FIG. 1; and,

FIG. 8 is a back end view of the dual reciprocating saw of FIG. 1.

The broken lines are included for the purpose of illustrating non-claimed subject matter and form no part of the claimed design.
